UNITED STATES PATENT OFFICE.

FRED J. KLINE, OF LONG ISLAND CITY, NEW YORK.

LOCK FOR PAPER FASTENERS.

Application filed June 17, 1926. Serial No. 116,540.

My present invention relates to an improved form of cheap and simple locking device for use with the well known two pronged metal fasteners commonly used for fastening 5 papers together.

Where pronged fasteners made of soft metal are used to fasten a considerable number of sheets by being thrust through a perforation in the bundle and bent apart flat 10 against the sheets, the bundle so fastened is often handled in a manner to bring a considerable strain or weight at the flexures of the prongs. Inasmuch as these pronged fasteners have to be made of very soft metal to permit 15 of easy and frequent bending without breaking, this strain often acts to bend the prongs upward and thus to loosen the whole bundle.

My present invention overcomes this difficulty by providing a simple form of locking 20 device which can be slipped over the prongs of the fastener when this latter is inserted, and can be instantly and easily brought into position to secure the prongs tightly in the fastening position. This is accomplished by 25 locking the soft metal prongs at points quite close to the perforation in the papers through which the prongs pass, thereby securing a firm purchase and entire security against pulling 30 the bundle loose.

The preferred mode of operating my improved locking device involves very little bending of the same and it can therefore be made stiff enough to be relied upon to resist 35 any pull to be expected in use.

At the same time it is one of the advantages 40 of my invention that the lock can be removed just as easily and quickly as it is applied. My locking device takes up a minimum of space and presents no parts which can catch the 45 fingers or become broken off.

A preferred embodiment of the invention is 50 illustrated in the accompanying drawings, wherein Figure 1 is a face view of a blank as stamped out to form one of my improved locks, Figure 2 is a similar view of the completed lock after final bending, Figure 3 is a cross sectional view on the line 3-3 in Figure 2, Figure 4 is an edge view of the same 55 showing the preferred "dished" form, Figure 5 is a plan view of a fastener in place on a bundle of papers, showing the lock in open position, Figure 6 is a view in section through the paper bundle, showing the fastener and 60 lock in edge view with the lock ready to be closed down on the fastener prongs, Figure 7

is a plan view of the fastener and lock in fully closed position on a bundle of papers, and Figure 8 is a partial cross sectional view taken on the line 8-8 in Figure 7.

In forming my improved locks I first stamp out flat blanks of the general form shown in Figure 1, from sheets of thin tinned sheet steel or other appropriate material. The device so formed comprises a central body 10 having a central perforation 11 adapted to be slipped over a pair of fastener prongs and to permit the turning of the device upon said prongs. This central body has two similar and symmetrically arranged extensions 12 and 13, extending in opposite directions as indicated by the arrows in Figure 1, and separated from the central body by narrow spaces 14, 15, for accommodation of the fastener prongs as hereinafter described.

The blanks so formed are finished, either in the same operation as the stamping or in a separate operation, by bending the extensions so as to be concave underneath, as at 16 in Figure 3, which is to accommodate a prong of the fastener on each side (see Figure 8). The dotted lines in Figure 1 show the limits of the beaks preferably formed at the open end of each extension 12, 13, whereby the lock is prevented from accidental turning when closed, and whereby accidental catching of the extensions is also prevented.

While not entirely essential to my broad invention, I prefer to manufacture these locks in a form indicated more or less exactly in Figure 4. That is to say, I prefer to give each lock a longitudinal bend or "dishing", making it concave upward, so that, when applied to the fastener prongs, it will be at once ready to be swung into fastening position, and by its very form, will suggest to the user how it should be applied and used.

The mode of use of my invention is made clear in Figures 5 to 8 inclusive.

A bundle of papers is shown, in section in Figures 6 and 8 and in plan in Figures 5 and 7, at 17. These are perforated in the usual manner, and the prongs of a fastener 18 are thrust through the perforation, as indicated in dotted lines in Figure 6. The prongs 18 are then passed through the opening 11 of my improved lock, with the longer dimension of the lock at right angles to the direction of bending of the prongs.

The lock is brought down close against the paper in the position stated, and the prongs 18 are then bent down in the usual manner.

Figure 5 shows the position of the various parts at this stage. The lock is then rotated around the prongs in the direction of the arrows in Figure 5, which brings them into the 5 position shown in Figure 6, with the extensions 12 and 13 over the prongs 18.

With the parts in this position pressure is applied by the fingers to the extensions 12 and 13, preferably bending the papers 17 and 10 prongs 18 at the same time, and these extensions are thus brought flat down upon the prongs in their closed position, as shown in Figures 7 and 8. The prongs 18 are confined under the concaves 16 of the extensions 15 12 and 13 as shown in Figure 8, and are thereby securely locked in place.

As clearly shown in Figure 7, the stiff extensions 12, 13, are firmly pressed down upon the flattened prongs 18, close to their flexure, 20 and any tendency to bend these prongs outward to loose the papers is firmly resisted.

If it be desired to loosen or separate the papers at any time, they can be easily bent, together with the prongs 18 and the extensions 12, 13, to reproduce the "dished" condition of the lock shown in Figure 4, and then reflexed together with the prongs 18, so as to free these last entirely from the lock. This latter can then be revolved into the position shown in Figure 5, and the prongs can 30 be straightened to permit removal of the lock and separation of the papers.

The security afforded by the use of my improved lock makes it possible in many cases 35 to fasten bundles of papers with adequate security with a single fastener.

The principle of my invention is capable of embodiment in forms differing materially from that herein shown, and I do not limit 40 myself to the details herein shown and described.

What I claim is—

1. In a locking device for sheet material, a 45 pronged paper fastener adapted to be inserted through said sheet material, a body adapted to revolve freely around the fastener when strung thereon, and means on said body

adapted to be brought into or out of locking engagement with the fastener as said body is turned around the fastener in one direction 50 or the other.

2. A locking plate for pronged paper fasteners adapted to be revolved thereon and comprising dished confining means adapted to be flattened down on the fastener prongs. 55

3. A locking plate for pronged paper fasteners comprising a revolvable body having a central aperture and a notch on each side of said aperture, and oppositely directed extensions located at the side of said notches remote 60 from the central aperture and adapted to lie over and confine the prongs of the fastener.

4. In a locking device for sheet material, a pronged paper fastener adapted to be inserted through said sheet material, a plate 65 of bendable material adapted to be strung over the prongs and revolve thereon and provided with confining means for said prongs.

5. In a locking device for sheet material, a pronged paper fastener adapted to be passed 70 through the paper and have the prongs thereof bent downwardly, a central substantially flat body having two locking extensions bent slightly upwardly from said body to engage one of the downwardly bent prongs of the 75 fastener when the entire device is revolved on the fastener.

6. A locking device for pronged paper fasteners, comprising a plate having a central aperture and a notch located on each side of 80 said aperture, and oppositely directed extensions at each end of the plate and on the side of said notches remote from the aperture.

7. A locking device for pronged paper fasteners, comprising a plate having a central aperture and a notch located on each side of 85 said aperture, and oppositely directed extensions at the ends of the plate located on the side of said notch remote from the central aperture and raised above said plate. 90

In testimony whereof I have hereto affixed my signature on this 14th day of June, 1926.

FRED J. KLINE.
